UNITED STATES PATENT OFFICE.

HARRY E. SMALL, OF NORFOLK, VIRGINIA.

GAME APPARATUS.

1,279,465.

Specification of Letters Patent. Patented Sept. 17, 1918.

Application filed March 1, 1918. Serial No. 219,896.

To all whom it may concern:

Be it known that I, HARRY E. SMALL, a citizen of the United States, residing at Norfolk, in the county of Norfolk and State of Virginia, have invented new and useful Improvements in Game Apparatus, of which the following is a specification.

This invention relates to games, and the object is to provide a device including a board on which is mounted a toy gun or the like for discharging a missile or marble through a chute member toward a target which may carry the representation of a man's face, an opening being provided for the mouth and a tongue extending through the opening but being normally held in a retracted position until released by the impact of the missile.

A further object is to provide in a game of the type indicated a target member carrying the representation of a man's face, an opening being provided for the mouth, and a tongue being pivotally mounted on the rear side of the target and normally held in a retracted position by means of a suitable device thrown out of engagement upon impact of a missile discharged in the manner specified.

A still further object is to provide in connection with a gun for discharging a missile or marble used in the game an adjustable guiding member for directing the missile toward the target.

In the drawings:

Figure 1 is a perspective view.

Fig. 2 is a vertical longitudinal section.

Fig. 3 is a detail view in elevation.

In carrying out my invention I employ a board 10 comprising a bottom member 12 having a series of perforations therein, each numbered to indicate a score with which a player is to be credited when he discharges a missile from the gun, described below, and this missile rolls backwardly into the board 45 and into one of the aforesaid apertures.

The front of the board is designated 14 and the side portions are shown at 15 and 16, the front member being provided with an aperture through which extends the 50 plunger 17 of a toy gun for discharging marbles or other suitable missiles used in the game. The barrel of the gun is designated 18, and the breech comprises a plate U-shaped in cross section and provided with

outwardly extending flanges 19 connected 55 with the bottom member 12 of the board.

Extending in alinement with the barrel of the gun is a chute 20 upwardly inclined toward the rear end thereof and provided with flanges 21 for guiding the marbles. 60 The extreme end of the chute comprises a member 22 which may be deflected to the desired angle. On the underside of the chute near the rear end thereof is a supporting device 24.

The target comprises a member 26 on which may appear the representation of a man's face having a comical expression, the target being known as the "nigger." An opening 27 is provided and represents the 70 mouth, and the object of the game is to direct the marbles through the mouth. A tongue 28 is pivotally mounted at 29 in ears or brackets 30 and is deflected as shown, so that when it is allowed to drop into position 75 by gravity it will assume position with the free end of the tongue projecting through the mouth, showing that the marble has reached the desired point. The tongue is held in retracted position by means of an 80 arm designated 32 mounted at 33 in a bracket or brackets 34. This arm is so proportioned that when thrown upwardly the extreme end thereof will engage the rear of the target at a point above the mouth and a 85 bowed portion of the arm will engage the extreme end of the tongue, retaining the tongue in retracted position.

In the use of the device it is intended that every player shall be provided with five 90 marbles and that when one of these marbles is shot through the opening in the target the player will be entitled to a count of 50. The marbles missing the center of the target or the mouth and rolling downwardly into 95 the table or board will be credited according to the opening in which they come to rest. The player obtaining the highest count or score after exhausting the allotment of five marbles wins the game.

100

What is claimed is:

1. In a device of the class described, a board, a toy gun mounted thereon, a target opposite said gun and having an opening therein, a chute between the gun and target, 105 and a pivotally mounted indicating device carried by the target and movable by gravity through the opening, and releasing means

projecting across the opening to be engaged by a missile passing therethrough.

2. In a device of the class described, a board provided with a plurality of openings therein, a toy gun mounted on the board, a chute for directing missiles discharged from the gun, means for deflecting the missiles in a given direction from the chute, a target having an opening therein, and a pivotally mounted member carried by the target and adapted to drop into said opening.

3. A board, a toy gun mounted thereon, a target carried by the board and comprising a board or the like having an opening therein and carrying a comical representation, a pivotally mounted tongue carried by the board on the rear side thereof, and means for nor-

mally holding said tongue in retracted position, and allowing the latter to drop into position within the opening of the board.

4. A target comprising a board or the like having an opening therein, a tongue pivotally mounted on the rear of the board at a point spaced from the opening for said tongue, and including a deflected portion, and a pivotally mounted arm mounted on the board at the side of the opening opposite to that on which the tongue is mounted, said arm when in operative position engaging the free end of the tongue and holding the latter in retracted position and out of the opening in the board.

In testimony whereof I affix my signature.

HARRY E. SMALL.
